UNITED STATES PATENT OFFICE.

JEAN FRANCIS WEBB, OF NEW YORK, N. Y.

SAFETY ALIGHTING ATTACHMENT FOR FLYING-MACHINES.

1,011,683.

Specification of Letters Patent. Patented Dec. 12, 1911.

Application filed October 17, 1910. Serial No. 587,502.

To all whom it may concern:

Be it known that I, JEAN FRANCIS WEBB, residing at New York, in the county of New York and State of New York, have invented 5 a new and Improved Safety Alighting Attachment for Flying-Machines, of which the following is a specification.

In the art of aerial navigation as at present practiced, there have come into use essentially two distinct types of machines, the lighter than air type and the heavier-than-air type. It is to the latter type that the present invention more particularly has reference. The heavier-than-air machines 15 usually include one or more supporting planes mounted on a keel frame or chassis, an elevation rudder, a direction rudder, stabilizing devices and a propelling mechanism whereby the machine is driven forward with a velocity that is sufficient to cause the force of the air against the under side of the sustaining planes, to sustain the machine in the air. Should the speed of the machine fall below a predetermined amount, 20 (other things being equal) the force of the air current will not suffice to overcome the action of gravity and the machine will fall to the earth.

My invention therefore has for its object 30 to provide a means which may be brought into action by the aviator at will and which is particularly designed to be brought into action when the machine becomes disabled, or when, for any reason, the machine begins 35 to drop toward the earth and becomes unmanageable. To this end I provide one or more parachute members which ordinarily are folded up and held on top of the machine in a compact space, the parachute 40 members being guyed to the machine. An air anchor is also provided whose function it is to drag the parachute or parachute members into position to permit the air to enter beneath the same and open them up to 45 sustain the machine sufficiently to break its fall, thereby permitting the machine to descend at a safe speed.

My invention also includes a housing for the parachute members and anchor whereby 50 the same may be compactly held when not in use.

The invention further includes an ejector for delivering the anchor and parachute out of the housing, means being also provided 55 for instantly opening the anchor to cause it to "hold" as soon as it leaves the housing.

A further object of this invention is to provide air ships of any form with a light but very powerful sustaining parachute device that in time of danger from the stopping of the motor, or from any disabling cause, can be instantly thrown into the air by the aviator, where it automatically opens up and expands its sections, and yet is so light and compact that when "nested" and packed into a suitable carrying case it offers little or no air resistance in ordinary flight.

Those novel details of construction, combination and arrangement of parts herein-after described and claimed also constitute a part of my invention.

In the drawings: Figure 1, is a perspective view showing my invention in use. Fig. 2, is an enlarged side elevation of the parachute sections showing the manner of attaching them to the flying machine. Fig. 3, is a side elevation of the air anchor in use. (Figs. 2 and 3 may be read as one figure by joining the lines A—B). Fig. 4, is an enlarged central section of the air anchor 80 frame, the same being shown open in full lines and partly closed in dotted lines. Fig. 5, is a view of the parts shown in Fig. 4 folded up. Fig. 6, is a section on the line 6—6 of Fig. 4. Fig. 7, is a top plan view 85 of the top of the anchor frame. Fig. 8, is a detail perspective view of the rib opening spring plate and one of the springs. Fig. 9, is a central vertical longitudinal section of the carrying case showing the anchor and 90 parachute members folded up into the same. Fig. 10, is a top plan view of the case open. Fig. 11, is an end view of the case positioned as shown in Fig. 9. Fig. 12, is an end view of the case positioned as shown in Fig. 10. 95 Fig. 13, is an enlarged detail sectional view of the case locking mechanism. Fig. 14, is a detail perspective view of one of the lid hinges. Fig. 15, is an end elevation of a modified form of the invention in use. Fig. 16, is an enlarged sectional view of the form shown in Fig. 15 when the parts are packed into their case. Fig. 17, is a diagrammatic end elevation of a modification of the form shown in Figs. 15 and 16.

Referring now to the accompanying drawings, in which like letters and numerals of reference indicate like parts in all of the figures, 1 designates the flying machine which may be of any type, (a machine of 110 the well-known Wright type being illustrated in the drawings). The sustaining

planes 2—2 of the machine are held on the keel frame or chassis 3, an altitude rudder 4 and a direction rudder 5 being provided together with the propelling mechanism 6, 5 all of which may be of the usual type.

7 designates the parachute members, one or more of which may be used, depending upon the weight of the machine to be sustained. Each parachute member 7 is composed of an inverted cup-like body 8 of silk or other suitable material, over which the strengthening cords or mesh 9 are secured. The cords 9 are connected at 10 with the main supporting cable 11 and radiate outwardly to the rim cord 12 of the respective sections. The lower end of the cable 11 has a ring 13 to which the ends of piano wire slings 14 are secured. The wires 14 passing down and around the machine, as at 15 to 10 sustain the machine on an even keel; the wires 14 each may be made to pass through the tubing of the keel frame, if desired. The rim cord 12 of the lower parachute 7 is connected by suitable cords 16 with the 15 framework of the machine 1, and by cords 17 it is also joined to the wires 14. When a series of parachute members 7 are employed the upper ones are joined to the lower ones by cords 18 that connect the several rim 20 cords 12, as shown in Figs. 1 and 2 of the drawings. The cable 11 continues above the parachute sections 7 a suitable distance and is joined at its upper end to what I term an "air anchor" the purpose of which will 25 more fully appear later. The air anchor which forms an important part of my invention is best shown in Figs. 1 and 3 to 8 inclusive of the drawings, by reference to 30 which it will be noticed that a central rod 40 19 has a ring 20 at its lower end for the cable 11, and is provided with a cup-like casing 21 near its lower end into which a coil spring 22 on the rod 19 projects. 23 designates a collar that is mounted on the rod 19 45 between which and the spring casing 21 the spring 22 is held, a stop 24 being provided on the rod 19 to limit the upward movement of the collar 23 under the influence of the spring 22. At the upper end the rod 19 50 has a fixture 34 having bearings 35 in which the rib sockets 36 are hinged as at 38, stops 37 limiting the opening movement of the ribs 31. The ribs 31 are made of ash, or other suitable material, that will be light, 55 strong and flexible, and they are fitted into and secured to the sockets 36. At their outer ends the ribs 31 have socket members 29 over the buttons 30 of which the covering 42 is fastened. Hinged to the collar 23 60 at 26 are brace members 25 each of which is composed of two sections that are hinged together at 27, one section being hinged at 26 to the collar 23 and the other section being hinged at 28 to the socket 29. Each 65 rib 31 has a stop shoulder member 32 in the

recess 33 of which the hinge joint 27 of the respective brace is adapted to lie when the parts are folded up, as shown in Fig. 5. In order to open the ribs 31 fully, coil springs 41 are mounted in slots 40 of a ring 70 39 that is fastened to the rod 19 near the top end of the same, one end of which spring 41 being held against the rod 19, while its other end engages a rib 31 to continuously tend to "open up" the frame. The anchor 75 frame thus formed is covered by a suitable cover 42 which is sewn to the ribs 31 and has a central opening over which the mouth of a balloon bag 43 may be secured, a suitable cord mesh being fitted over the whole 80 to strengthen the anchor. In practice either the spring 41 or the spring 22 may be omitted, or both may be used, if desired, so long as a quick initial opening of the anchor is obtained. 85

In practice under normal conditions the parachute members 7 and the anchor 45 are compactly folded away in a suitable carrying case 46 on top of the machine. The case 46 which is best shown in Figs. 9 to 90 14 inclusive, consists of a shell formed of aluminum or other light and strong material, the same being composed of a lower half section 47 and two upper quarter sections or lids 48—48. The ends 49 of the 95 case 46 are of coniform to reduce the air resistance and the case is mounted in the central longitudinal plane of the machine by brackets 50 clamped at 51 to the keel frame 3 of the flying machine 1. The lid 100 sections 48 are hinged to the lower section 47 by spring hinges 52 (see Fig. 14) which are designed to open the lids 48 when they are released. The lids 48 are held closed by a suitable locking device, preferably that 105 shown in Fig. 13 of the drawings, by reference to which it will be observed that one lid section 48 has a longitudinal reinforced or strengthening bead 53 having a hole 54 to receive the main latch bar 55 that is carried by the lever 56. The other lid has a corresponding bead or reinforced strip 57 that also has a hole 58 for the pin 55, the strips 53 and 57 overlapping one another. The lever 56 is fulcrumed at 59 in a bearing fork 60 on one of the latch members. The latch bar 55 has a latch notch 61 for the pin 62 that is pressed by a spring 63 into engagement with the bar 55 and holds the bar 55 with its free end located within the hole 58 when the latch is released so as not to project and interfere with the ready removal of the contents of the case or provide an obstruction against which the 110 parachute cords or wires may engage. 115

The case 46 has a depressed portion 64 in its bottom in which the ejector mechanism lies when the parts are housed. The ejector mechanism consists of a light hollow forked frame 65 secured to the ends of 120 130

5 torsional springs 66 which wrap around a pin 67 in the depression 64, the frame 65 may be covered by a web 68, if desired, to prevent any possible entanglement between the ejector and the parts to be ejected.

10 The lever 56 may be rocked to release the lids 48 by a cord 69 that runs to a position where it may be conveniently grasped by the aviator.

15 When several parachute members are employed they are made to fit one within the other, or to "nest," as it were. The several members 7 are first "nested" and then folded up umbrella fashion, after which they are let into the case 46 (the ejector being held down in any suitable way) see Fig. 9, the anchor 45 is closed up and folded into the case on top of the parachute member 7, (see Fig. 9) after which the lids 48 are closed 20 and the latch 62 released to permit the spring 93 to project the bar 55 into the hole 54 and thereby hold the lids closed. The guy wires 14 and cords 16—17 are allowed to project through openings 70 in the lids 25 48, (see Fig. 9).

30 The parachutes 7—7 and the anchor 45 being now orderly packed in the case 46, the aviator runs the machine in the usual manner. Should, for any reason, the headway of the machine be lost, or 35 should the aviator lose control of the machine, thereby allowing it to fall to the earth, the aviator need only pull the rope or cord 69 to move the lever 56 to raise the latch bar 55 and release the lids 48, where-

40 upon the ejector will throw the contents of the case upwardly and forwardly out of the case, the anchor 45 instantly opening up to catch the air and form a "drag," as it were, thereby pulling the parachute members 7 apart, as shown in dotted lines in Fig. 2. The air will then quickly enter beneath the parachutes and extend them to their full capacity, as shown in Fig. 2 of the drawings, thereby quickly forming an effective sus- 45 taining means for the machine which will be righted and held on an even keel, the whole structure settling slowly and safely to the earth. When the anchor 45 is first opened the balloon bag 43 quickly fills with 50 air and is extended to the position or form shown in Fig. 1, thereby increasing the effective operation of the anchor which by serving as a "drag" assists the members 7 in sustaining the machine in the air until it 55 settles slowly to the earth.

60 Numerous modifications and adaptations of the invention may readily become manifest to those skilled in the art and I do not wish to limit myself to the use of the form hereinbefore described, although the same is a preferred form.

65 In the modified form shown in Figs. 15 and 16 a vertical tubular casing 71 is carried by the flying machine 1. The casing 71 is made of a light thin material, such as

aluminum. Within the casing a piston 72 is mounted, its movement being limited by the cable 73 that is secured to it at 74 and to the bottom of the case at 75. The piston 72 carries a series of telescopic pipes 76 70 whose extension movement is limited by collars 77. The inner pipe forms the rod support for the air anchor 45, which anchor may otherwise be constructed as in the preferred form of the invention disclosed particularly in Fig. 4. The pipe rod section 76 terminates in an air chamber 78 and the pipes 76 are in communication with the casing 71 below the piston 72. The parachute members 7 have ring-like openings 79 so they may fit over the pipes 76 and they are connected by cords 80 to one another and to the fixed ring 81 of the inner pipe section 76 that forms the anchor rod. In other respects the construction of the 85 parachute members 7 may be identical with the preferred form disclosed hereinbefore, and they may also be similarly guyed together and to the flying machine. Normally the parachute members 7 are nested 90 and packed into the case 71 (see Fig. 16) and the anchor 45 is folded into the case where its tendency to open holds the parts in the case 71 by friction. 82 is a tank containing compressed air which is piped up 95 at 83 with the case 71 below the piston 72, a valve 84 controlling the admission of air to the case. 85 is a valve operating lever that is extended to a position within convenient reach of the aviator, by means of 100 which he may open the valve 84 and permit compressed air to enter the case 71 from the tank 82 to force the piston 72 upwardly and extend the telescopic sections 76 thereby ejecting the parachute members and the air 105 anchor from the case 71. A cord 88 may be secured at 86 to the piston 72, and pass over a pulley 87 from which it extends to a position in convenient reach of the aviator by means of which the contents of the case may 110 be ejected in the event that the supply of compressed air gives out.

115 The form shown in Fig. 17 is a modification of the form shown in Figs. 15 and 16 and in this form the air tank 82 is connected with the case 71 by a flexible pipe 89 and the case 71 in this form is hinged at 90 to a bracket 91 and lies on top of the flying machine in a crotch 92. The operation of this form differs but slightly from that form 120 shown in Figs. 15 and 16. In this form the contents of the case 71 are ejected in a horizontal direction whereas in the form shown in Figs. 15 and 16 they are ejected in a vertical direction. As soon as the contents of 125 the case 71 have been ejected the case 71 will assume a vertical position due to the air going under the parachute members 7 and the anchor 45 and will thus support the flying machine 1.

From the foregoing description it will be noticed I have provided a simple and effectively constructed safety appliance for the purposes specified. The same can be cheaply manufactured at a low gross weight and when not in use it takes up little room and offers little or no air resistance or impediment to the normal action of the flying machine.

10. What I claim is:—

1. A flying machine that includes in itself sustaining means, a propelling mechanism and devices for controlling its movement; combined with a plurality of serially arranged normally inactive parachutes nestable one within the other for sustaining said flying machine when said flying machine falls.

2. A flying machine that includes in itself a sustaining means, a means for controlling the movement of the flying machine through the air; combined with a plurality of serially arranged foldable normally inoperative parachutes nestable one within the other and mounted on said flying machine, and means for unnesting said parachutes to bring said parachutes into operation to sustain said flying machine in falling.

3. A flying machine, combined with a parachute, connections between the said parachute and said flying machine, a carrying case for said parachute mounted on said flying machine, and aviator controlled means for mechanically flinging or casting said parachute out of said case, said means including a pivoted casting arm.

4. A flying machine combined with a sustaining parachute connected thereto, an air anchor connected with said parachute to hold it in position to open, and a carrying case into which said parachute and said anchor is foldable.

5. A flying machine combined with a sustaining parachute connected thereto, an air anchor connected with said parachute to hold it in position to open, a carrying case into which said parachute and said anchor may be folded, and means for opening said case to release said parachute and anchor.

50. 6. A flying machine combined with a sustaining parachute connected thereto, an air anchor connected with said parachute to hold it in position to open, a carrying case into which said parachute and said anchor may be folded, means for opening said case to release said parachute and anchor, and means for ejecting said anchor from said case.

60. 7. A flying machine combined with a sustaining parachute connected thereto, an air anchor connected with said parachute to hold it in position to open, a carrying case into which said parachute and said anchor may be folded, means for opening said case to release said parachute and anchor, and

means for ejecting said parachute and said anchor from said case.

8. The combination of a flying machine, a foldable sustaining parachute therefor, a foldable air anchor connected with said parachute, and a single releasable holder for said parachute and said anchor, together with automatic means for opening said anchor when released from said holder.

9. A flying machine, a plurality of 75 parachute members nestable one within the other and foldable while nested, connections between said parachute members and said flying machine, a single carrying case for said members, and means for opening said case 80 to release said members.

10. A flying machine, a plurality of 85 parachute members nestable one within the other and foldable while nested, connections between said parachute members and said flying machine, a single carrying case for said members, and means for throwing all of 90 said parachute members out of said case.

11. A flying machine, a nest of 95 parachute members connected thereto to support said machine, an air anchor connected to said parachute members, a single means for holding the said parachute members and said anchor folded together on the machine when not in use.

12. A flying machine, a nest of 100 parachute members connected thereto to support said machine, an air anchor connected to said parachute members, means for holding the said 105 parachute members when nested and said anchor, folded together on the machine when not in use, and means for releasing said holding means to permit said anchor to drag said parachute members into position to be opened by the air entering the same.

13. In a flying machine, a nest of 110 flexible parachute members, a foldable air anchor connected to the same, means continuously tending to open said anchor, a single carrying case for all of said 115 parachute members and said anchor, and means for ejecting all of said members from said case to permit said anchor to open and thereby drag and cause said parachute members to unnest and come into position to be opened by the air 115 entering the same.

14. In a flying machine, a flexible 120 parachute member flexibly secured to the top of said machine, an air anchor flexibly secured to the top of said 125 parachute member, a single carrying case for said parachute and said anchor into which said anchor and 125 parachute may be folded, means for holding said 130 parachute and said anchor in said carrying case, means for releasing said holding means, and means in said carrying case for throwing said 130 parachute member and said anchor simultaneously out of said carrying case when open.

15. In a flying machine, a plurality of 130

- serially arranged nestable and foldable parachute members, a foldable air anchor serially connected to said parachute members, a single carrying case for all of said parachute members and said anchor and into which said parachute members when nested may be folded and into which said air anchor when folded may be placed, means continuously tending to open said air anchor, 10 means continuously tending to throw all of said parachute members and said air anchor out of said carrying case, releasable means for holding said carrying case closed to retain said parachute members and said air anchor and prevent the operation of said throwing out means.
16. An air anchor, a cable depending therefrom, a flying machine suspended from said cable, a parachute on said cable, guys 20 joining said parachute to said flying machine, and a carrying case on said flying machine into which said parachute and anchor may be stored when not in use.
17. An air anchor, a cable depending therefrom, a flying machine suspended by said cable and a plurality of parachutes on said cable said parachute members being nestable one within the other.
18. The combination of an aeroplane with a parachute, consisting of a multiple of 30 units that telescope or nest into each other in whole or in part.
19. A cigar-shaped carrying case consisting of a bottom half section having a longitudinal depression in its bottom, a spring 35 actuated ejector pivotally mounted in said depression to lie therein, a pair of lid sections hinged to said bottom section to close over the same, means for latching said lid sections together, means for moving said 40 latching means to release said lid sections, and means for holding said latching means in its releasing position.
20. A cigar shaped carrying case consisting of a bottom section and a lid section, 45 a spring actuated ejector pivotally mounted in said bottom section, means for latching said lid section closed, means for moving said latching means to release said lid section, and means for holding said latching 50 means in its releasing position.
